J. F. O'CONNOR.

TANDEM DRAFT GEAR FOR RAILWAY CARS.

APPLICATION FILED JUNE 11, 1919. RENEWED MAY 2, 1921.

1,382,221.

Patented June 21, 1921.

UNITED STATES PATENT OFFICE.

JOHN F. O'CONNOR, OF CHICAGO, ILLINOIS, ASSIGNOR TO WILLIAM H. MINER, OF CHAZY, NEW YORK.

TANDEM DRAFT-GEAR FOR RAILWAY-CARS.

1,382,221.

Specification of Letters Patent. Patented June 21, 1921.

Application filed June 11, 1919, Serial No. 303,498. Renewed May 2, 1921. Serial No. 466,219.

To all whom it may concern:

Be it known that I, JOHN F. O'CONNOR, a citizen of the United States, residing at Chicago, in the county of Cook and State 5 of Illinois, have invented a certain new and useful Improvement in Tandem Draft-Gears for Railway-Cars, of which the following is a full, clear, concise, and exact description, reference being had to the accompanying drawings, forming a part of this 10 specification.

My invention relates to improvements in tandem draft gears for railway cars.

Cars now being built under the authority 15 of the United States railroad administration require that they shall be provided with draft rigging stops, spaced apart to accommodate friction gears now on the market. This requires the use of a single pocket draft 20 strap and prevents the use of tandem stop castings having end stops and intermediate stops. Many railroads desire not to employ friction gears and have made tandem spring gears standard upon their railroad equipment. Consequently, there is a present 25 need for tandem spring gears which may be employed in the now standard construction made such by the railroad administration and with which friction gears employing a 30 single pocket yoke may be interchanged without any modification of the stops.

One of the objects of this invention is to provide a tandem gear for railway cars which may be used in standard constructions 35 now being built under the authority of the United States railroad administration and which do not employ the old form of tandem yoke having and requiring a centrally disposed yoke thimble. Another object is to 40 provide a tandem spring draft rigging upon which only front and rear sets of stops are used and in which the pressure transmitting means from the end followers to the remote 45 springs are made stronger and more effective than heretofore, and one in which the pressure transmitting elements may be simple foundry castings.

In the drawings forming a part of this 50 specification, Figure 1 is a longitudinal horizontal section of a draft rigging embodying my invention. Fig. 2 is a vertical transverse section taken on line 2-2 of Fig. 1. Fig. 3 is an elevation showing the pressure transmitting means and their relative posi-

tions when assembled. Fig. 4 is an end view 55 of one of the intermediate followers which my device employs.

Referring to the drawings, the numeral 10 indicates draft members or center sills to which, in the usual manner, are secured the 60 front stop members 11-11 and the rear stop members 12-12, the same being spaced apart the present standard distance, to-wit: 24-5/8 inches. The numeral 13 indicates a draw bar only the rear end thereof being 65 shown, to which a yoke member 14 is secured and which is of a single pocket type. Within the single pocket of this yoke are located the front and rear followers 15 and 16, respectively. 70

Between the followers 15 and 16 I interpose the following shock absorbing means: Tandem springs A-A are employed, each of which preferably consists of an outer heavy coil and an inner lighter coil. Said 75 springs are contained within counterpart casings B-B, hereinafter described in detail, and between the springs is interposed a pair of what may be termed intermediate followers C-C. 80

Each casing B is of substantially hollow rectangular form throughout its length and open at each end. The same are preferably made in the form of castings and may be cored, as indicated at 17-17, in order to 85 lessen the weight. At its inner end, that is the end remote from the corresponding follower which the casing B engages, each casing is recessed on opposite sides, as indicated at 18-18, for a distance not less than 90 the sum of thickness of one of the intermediate followers C and the permissible stroke of the mechanism. The recesses 18 are defined on the edges thereof by radially extending faces, as indicated at 20-20 in 95 Fig. 2.

Each of the intermediate followers C is also preferably in the form of a casting and is of generally circular form, as indicated at 100 21 in Fig. 4. Formed on diametrically disposed sides of the circular section or disk of the follower C are laterally extending flange-like sections 22-22. The outer edges thereof, indicated at 23-23, are adapted to extend substantially flush with the corresponding outer surfaces of the walls of the casings B, and the upper and lower edges of said flanges 22 are formed on inclines, as indi- 105

cated at 24—24, to correspond with the inclined or beveled edges 20 of the shells B to thereby form a sliding fit.

The parts are assembled as shown in the drawing—that is, one casing B and its directly actuated intermediate follower C is disposed at an angle of 90° to the other casing B and its corresponding associated intermediate follower C. In this way, one casing B will directly engage the flanges 22 of one follower C and the latter will be able to slide within the recesses 18 of the other casing B. As will be evident from an inspection of Fig. 1, upon relative approach 15 of the followers 15 and 16, the intermediate followers C will move correspondingly, thus simultaneously compressing the tandem springs A—A without the use of any tandem yoke and intermediate thimble.

It will be noted that each of the casings B which I have provided may be manufactured readily and cheaply as a casting without the necessity of machining or use of expensive cores. The same is also true of 20 the intermediate follower C. Furthermore, there are no relatively delicate or weak radial fingers or prongs such as have heretofore been necessary in certain forms of 25 draft gears of the general character disclosed in this application, and which have prevented their successful use in actual service conditions. My arrangement involves a minimum number of parts, all of which are easily and cheaply manufactured, and the 30 entire device is extremely rugged and well able to withstand the heavy shocks now encountered in railway service.

The parts may be supported in any suitable manner but preferably I use a detachable saddle plate 25, and to center and guide the casing B, said saddle plate may be provided with guiding angles 26 riveted thereto, as clearly illustrated in Fig. 2.

I claim:

1. In a tandem shock absorbing mechanism, the combination with two aligned and relatively movable casings, of tandem arranged shock absorbing units within said casings, and a pair of centrally disposed detachable followers interposed between the shock absorbing units, each of said followers being engaged by one of the casings and slideable within the other casing, each casing being slotted at its inner end to accommodate slotted one of said followers.

2. In a tandem shock absorbing mechanism, the combination with two aligned and relatively movable casings, of tandem arranged shock absorbing units within said casings, and a pair of centrally disposed de-

tachable followers interposed between the shock absorbing units, each of said followers being engaged by one of the casings and slideable within the other casing, each of said followers being of disk-like form having 65 diametrically disposed flanges, the latter being directly engaged by the corresponding casing, each casing being slotted at its inner end to accommodate one of said followers.

3. In a tandem draft gear, the combination with front and rear main followers; of aligned, partially telescoped casings interposed between said followers; tandem arranged springs, one within each casing, each spring bearing at its outer end upon one of 70 said main followers; and a pair of intermediate followers detachably formed with respect to said casings, each of said intermediate followers engaging the inner end of one of said springs and adapted to be directly actuated by one of said casings, each of said intermediate followers being slideable with respect to that casing within which is disposed the spring in contact with said intermediate follower, each casing being 75 slotted at its inner end to accommodate the sliding movement of an intermediate follower.

4. In a tandem draft gear, the combination with front and rear main followers; of aligned, partially telescoped casings interposed between said followers; tandem arranged springs, one within each casing and bearing at its outer end upon the respective 80 main follower; and a pair of intermediate 85 followers separately formed with respect to the casings, one intermediate follower engaging the inner end of the spring in one casing and adapted to be directly actuated by the other casing; the other intermediate 90 follower engaging the inner end of the other spring and adapted to be directly actuated by the remaining casing, each intermediate follower being slideable with respect to that casing within which is disposed that spring 95 in contact therewith, each of said intermediate followers being of substantially disk form with diametrically disposed flanges having radially extending bearing faces on which the respective intermediate followers are slideable, said casing having co-operating radially extending bearing faces, each casing being slotted at its inner end to accommodate the sliding movement of the respective 100 intermediate followers.

In witness that I claim the foregoing I have hereunto subscribed my name this 28 day of May, 1919.

JOHN F. O'CONNOR
